(57) **CLAIM**

The ornamental design for a mini fascia gun as shown and described.

DESCRIPTION

FIG. 1 is a front, left, top perspective view of a mini fascia gun showing my new design;

FIG. 2 is a front view thereof;

FIG. 3 is a left view thereof;

FIG. 4 is a right view thereof;

FIG. 5 is a back view thereof;

FIG. 6 is a top view thereof;

FIG. 7 is a bottom view thereof;

FIG. 8 is an enlarged view of the encircled area 8 of FIG. 2;

FIG. 9 is an enlarged view of the encircled area 9 of FIG. 2;

FIG. 10 is an enlarged view of the encircled area 10 of FIG. 3; and,

FIG. 11 is an enlarged view of the encircled area 11 of FIG. 7.

The broken lines shown on the drawings depict portions of the mini fascia gun that form no part of the claimed design.
